(57) **CLAIM**

The ornamental design for a display screen with graphical user interface for a cooktop, as shown and described.

DESCRIPTION

FIG. 1 is a front view of a display screen with graphical user interface for a cooktop showing the new design in a first state;

FIG. 2 is a front view thereof in a second state;

FIG. 3 is a front view thereof in a third state;

FIG. 4 is a front view thereof in a fourth state;

FIG. 5 is a front view thereof in a fifth state; and,

FIG. 6 is another front view of FIG. 2, showing an example environment which forms no part of the claimed design.

The dot-dash broken lines show the display screen which forms no part of the claimed design. The remaining broken lines show portions of the graphical user interface which form no part of the claimed design.

The appearance of the transitional image sequentially transitions between the images shown in FIGS. 1-5. The process of period in which one image transitions to another image forms no part of the claimed design.

1 Claim, 4 Drawing Sheets
